US00D631130S

(12) **United States Design Patent**
Riedel

(10) **Patent No.:** **US D631,130 S**
(45) **Date of Patent:** **** Jan. 18, 2011**

(54) **CONNECTOR FOR A FAUCET MOUNTED WATER FILTER**

(75) Inventor: **Richard Paul Riedel**, Mason, OH (US)

(73) Assignee: **The Procter & Gamble Company**,
Cincinnati, OH (US)

(**) Term: **14 Years**

(21) Appl. No.: **29/368,125**

(22) Filed: **Aug. 18, 2010**

(57) **CLAIM**

The ornamental design for a connector for a faucet mounted water filter, as shown and described.

DESCRIPTION

FIG. 1 is a perspective view of a connector for a faucet mounted water filter illustrating my new design;

FIG. 2 is a left side elevational view thereof;

FIG. 3 is a right side elevational view thereof;

FIG. 4 is a front side elevational view thereof;

FIG. 5 is a back side elevational view thereof;

FIG. 6 is a top planar view of thereof; and,

FIG. 7 is a bottom planar view thereof.

The broken lines form no part of the claimed design.
